UNITED STATES PATENT OFFICE.

JOHN I. WILEY, OF LOS ANGELES, CALIFORNIA.

DISPLAY APPARATUS.

1,110,296.

Specification of Letters Patent.

Patented Sept. 8, 1914.

Application filed May 1, 1913. Serial No. 764,922.

To all whom it may concern:

Be it known that I, JOHN I. WILEY, a citizen of the United States, residing at Los Angeles, in the county of Los Angeles and State of California, have invented a certain new and useful Display Apparatus, of which the following is a specification.

My invention relates to a display apparatus for advertising, entertainment and educational purposes, and involves generally the kaleidoscopic principle of multiplication of objects.

In the accompanying drawings, Figure 1, is a front elevation of an apparatus embodying my invention. Fig. 2 is a sectional side elevation on lines 2—2, Fig. 1. Fig. 3, is a sectional plan, on lines 3—3, Fig. 1. Fig. 4, is a diagrammatic illustration of the multiplication of images produced by the 20 position of two reflectors at an angle of 36°. Fig. 5, is an elevation showing the embodiment of the invention in a rotary cabinet. Fig. 6, is a sectional illustration, the plane of section being taken on lines 25 6—6, Fig. 5; and Fig. 7, is a transverse section, on lines 7—7, Fig. 5.

The apparatus consists of a cabinet 1, of preferably a hemiholohedral cross section, provided with openings 2, 3 and 4, for affording observation of the interior of the cabinet from three points of view as shown, or from as many points as the polygonal division or structure of the cabinet will permit.

Within said cabinet and disposed perpendicularly to a base 5, are three sets or groups of mirrors 6, 7 and 8, severally consisting of two mirrors A and B, suitably fixed to wooden or other backings 9 and 10, 11 and 12, and 13 and 14, respectively, which are hinged together in the manner shown at 15, 16 and 17, whereby the edge of one mirror will be in substantially the same plane with that of the other mirror 45 of the particular group, the pintles 18, 19 and 20, for the respective hinges being extended through and supported by a transverse member 21. Each mirror backing is provided with an eyelet 22, for engagement

50 by a suitable device 23, secured to and depending from the top 24, of the cabinet and provided with an adjusting means, such as a turn-buckle 25, for giving to the mirrors the proper and most effective angle for

observation. The several mirrors A and B, in each set, face each other and form, as seen, two sides of a regular triangular prism, the widest divergence being toward the openings 2, 3 and 4. When an object is placed between the mirrors A and B, it obviously will appear to the observer as many objects arranged at the angle of a polygon, the number of reflections of the object being increased where the angle of the mirror forms a smaller aliquot part of 360°, and reduced where the angle forms a greater aliquot part. Thus an infinite variety of patterns, designs and conceptions may be produced by a multiplicity of objects, and by every alteration of their position. An additional 70 mirror 26, may be positioned in the cabinet above each set of mirrors, and at the proper angle, to reflect the reflected images or objects and make them visible to the operator from the rear of the cabinet through 75 the opening 27, so that all the objects and images become observable from the rear of the cabinet in substantially the same manner as from the front.

Display objects may be placed on the 80 aforementioned base 5, which is in the nature of an incline plane 28, the degree of inclination being gaged by and corresponding to the angularity of the bottom edge of the mirrors. This base is preferably hollow, as shown in Fig. 2, and furnished with a transparent cover 29, for the purpose of exhibiting transparent and translucent objects, illumination being obtained from any suitable source, as an incandescent light 90 30, and a reflector 31, within said base 5. Said base is movable to enlarge or diminish the aperture 32, at the bottom of the mirrors, in order to admit of the insertion of objects of various thicknesses. The particular form of the base, however, is immaterial, since it may be of any size and form, and may be revoluble with respect to the mirrors. Suitable lamps 33, and reflectors 34, placed above the mirrors may be used 100 for general illumination.

Figs. 5, 6 and 7, illustrate an apparatus designed chiefly for advertising and exhibition purposes. The cabinet 35, is revolubly mounted on a suitable stand 36, a train of 105 gears 37, transmitting power from a suitable motor 38. The mirrors 39, are fixed on a preferably cone-shaped base 40, on which

articles for display are placed, and illuminated by lamps 41, and reflectors 42, mounted in the hollow cover of the cabinet.

What I claim, is:

- 5 1. In a display apparatus, a cabinet having one or a plurality of openings in the front, one or a plurality of groups of mirrors perpendicularly disposed and suspended within said cabinet, said mirrors severally consisting of two mirrors having their rear edges in substantially the same plane and their reflecting surfaces toward each other, said two mirrors of each group being adjustable relatively to each other and having their greatest divergence toward said opening or openings, and a suitable support for objects below said mirrors, said support being movable to admit of the insertion of objects of various thicknesses. 60
- 10 2. In a display apparatus, a cabinet having a plurality of openings, a plurality of groups of mirrors within said cabinet severally consisting of two mirrors, perpendicularly disposed, and hinged together, said two mirrors of each group having their reflecting surfaces toward and being adjustable relatively to each other, a support for opaque and transparent objects, a source of illumination for the opaque objects, and a source of illumination for the transparent objects. 65
- 15 3. In a display apparatus, a cabinet having a plurality of openings, a plurality of groups of perpendicular mirrors disposed within said cabinet and forming two sides of a regular triangular prism, said mirrors facing each other and being hinged together whereby to vary the angle of the mirrors, the greatest divergence of said mirrors being toward said openings, and mirrors within said cabinet to make the objects reflected from the front of the cabinet visible from the rear. 70
- 20 4. In a display apparatus, a cabinet having a plurality of openings, a plurality of groups of mirrors within said cabinet, severally consisting of two mirrors hingedly connected and forming two sides of a regular triangle, the greatest divergence of said mirrors being toward said openings, and a base in said cabinet arranged to support objects, said base being below and movable relatively to said mirrors. 75
- 25 5. In a display apparatus, a cabinet having a plurality of openings, a plurality of groups of mirrors within said cabinet severally consisting of two mirrors hingedly connected and forming two sides of a regular triangle, the greatest divergence of said mirrors being toward said openings, a source of illumination for the cabinet, and a hollow movable base arranged to support objects, and having a transparent plate in the top, 80
- 30 6. In a display apparatus, a cabinet having openings in the front thereof, groups of perpendicularly disposed mirrors within said cabinet severally comprising two mirrors for each opening, facing each other and being visible from the front of said cabinet through one or all of said openings, an object-supporting base within said cabinet and below and movable relatively to said mirrors and 85 having a transparent top, a source of illumination from the top of said cabinet and a source of illumination in said base for translucent objects placed thereon. 90
- 35 7. In a display apparatus, a cabinet having openings in the front and an opening in the rear thereof, groups of perpendicularly disposed mirrors within said cabinet and severally comprising two mirrors for each opening, facing each other and being visible 95 from the front of said cabinet through one or all of said openings, and an object supporting base movable within said cabinet and relatively to said mirrors to diminish the aperture between the bottom of said mirrors and the top of said base, said support being operable through the opening in the rear of said cabinet. 100

In testimony whereof I have set my hand in the presence of two witnesses.

JOHN I. WILEY.
